[57] CLAIM

The ornamental design for a photograph display frame, as shown and described.

DESCRIPTION

FIG. 1 is a perspective view of a photograph display frame showing my new design;

FIG. 2 is a top plan view thereof; and

FIG. 3 is a side elevational view thereof, all sides being substantially identical.

The unshown bottom of the claimed design is substan-
